Inventor.

Joseph Sawyer

UNITED STATES PATENT OFFICE.

JOSEPH SAWYER, OF LONDON, ENGLAND.

FURNACE.

SPECIFICATION forming part of Letters Patent No. 235,458, dated December 14, 1880.

Application filed July 31, 1880. (No model.) Patented in England February 9, 1878.

To all whom it may concern:

Be it known that I, JOSEPH SAWYER, of London, England, have invented new and useful Improvements in Furnaces, (for which I have obtained a patent in Great Britain, No. 549, bearing date February 9, 1878, and sealed July 16, 1878,) of which the following is a specification.

This invention relates to improvements in furnaces.

In carrying out my invention I form the upper surfaces of the furnace-bars with semicircular projections, and for communicating motion to the said bars I provide two rocking front bearing-bars operated by lever-handles, by which they may be caused to slide in opposite directions. The bars are connected alternately to one of these rocking bars, by which means, if the said lever-handles be operated in opposite directions, the bars will have a to-and-fro motion communicated to them, each alternate bar moving in the opposite direction to the remainder, thereby clearing or breaking up, by means of the semicircular projections, the clinkers and scoria, and also separating them, effecting a more perfect combustion of the fuel by keeping free the air-spaces between the bars. The bars are preferably made hollow, and have lateral openings for the admission of air.

But to make my invention better understood, I will proceed to describe the same by reference to the accompanying drawings, in which—

Figure 1 is a longitudinal section, showing my improvements in furnaces applied to an ordinary Cornish boiler. Fig. 2 is a front elevation of the same, and Fig. 3 is a plan of the fire-grate.

Similar letters in all the figures represent similar parts.

40 *a a' a'* are the hollow furnace-bars formed with semicircular projections *b* on their upper surfaces, and with lateral openings *a²*, as shown in Fig. 1.

c c' are the two rocking front bearing-bars. 45 *d* and *e* are the lever-handles for operating the said rocking bars. The bars *a* are connected to and operated by the rocking bar *c* by means of the projections *f* taking into recesses in the under side of the front ends of the bars, the 50 remaining bars *a'* being connected with the rocking bar *c'* and operated in a similar man-

ner by projections *f'*. The outside bars, *a³*, are fixed.

g is a roller on which the bars rest. *i* is the dead-plate, which is placed, as shown, some 55 distance above the top of the bars, and extends in front of the door; *j*, air-grating between the upper surfaces of the bars and the under side of the dead-plate for the admission of air to the fuel. The back ends of the bars pass 60 through openings in the guide-plate *k* under the bridge *l*, and *h h* are guides for the front ends of the bars; or a guide or spacing-plate may be placed in any other suitable position.

From this arrangement it will be understood 65 that if the lever-handles *d* and *e* be operated in opposite directions the rocking bars *c c'* will communicate a backward and forward motion to the bars, the bars *a* moving in the opposite direction to the bars *a'*, thereby clearing 70 or breaking up, by means of the semicircular projections *b*, the clinkers and scoria, and thus the air passes freely between the bars, and at the same time it is introduced through the grating *j* under the dead-plate *i*, and through 75 the hollow bars out by the lateral openings *a²*, passing thoroughly into the fuel, and effecting a more perfect combustion thereof and consumption of the smoke.

It will be understood that when both levers 80 are pushed back the semicircular projections of the bars will correspond.

m is a chamber or jacket on the back of the furnace-door *n*, such chamber being open at the bottom, as shown in Fig. 1. *o* is a flap or 85 valve pivoting at the upper part of the chamber *m*. *p p p* are perforations in the furnace-door *n*. *q* is a rack-handle connected to the flap or valve *o*, and passing through an opening in the door, so as to allow of operating the 90 flap *o*; *r*, catch.

By this arrangement, if the flap *o* be closed against the door, as shown in Fig. 1, no air can pass through the perforations *p p* into the furnace; but if the flap be opened into the 95 position shown by the dotted lines the air will pass through the perforations *p* and down through the bottom of the chamber *m* into the furnace direct onto the fuel.

Having thus described my said invention 100 and the manner of performing the same, I wish it to be understood that I do not confine

myself to the precise details herein laid down, and shown in the drawings, as the same may be varied without departing from the peculiar character of my invention; but

5. What I do claim is—

1. Fire-bars for furnaces made hollow and with semicircular projections on their upper surfaces, and with lateral openings, (or of solid bars with semicircular projections,) in combination with a bearing roller or rollers and with suitable guides or spacing-plates, as described,

the whole arranged and operating as and for the purposes set forth.

2. An air-grating located under the dead-plate and above the grate-bars for the admission of air to the furnace, as hereinbefore described, and shown in the accompanying drawings.

JOSEPH SAWYER.
